US00D428500S

United States Patent [19]

Wederski

[11] Patent Number: Des. 428,500

[45] Date of Patent: ** Jul. 18, 2000

[54] WOOD-SIMULATING APPEARANCE FOR
FIBER-CEMENT SIDING

4,409,276 10/1983 Martinelli et al. 428/151

[76] Inventor: Scott Allen Wederski, P.O. Box 12800,
Prescott, Ariz. 86304

Primary Examiner—Doris Clark

[**] Term: 14 Years

[57] CLAIM

[21] Appl. No.: 29/105,566

The ornamental design for a wood-simulating appearance
for fiber-cement siding, as shown.

[22] Filed: May 27, 1999

DESCRIPTION

[51] LOC (7) Cl. 25-01

The FIGURE is a front perspective view.

[52] U.S. Cl. D25/150

The invention is in a thin, flat, sheetlike form with plain and
unornamented bottom, top, sides, and back; therefore, only
the front perspective is shown.

[58] Field of Search D25/139, 149,
D25/163, 150; 428/106, 151, 541
